UNITED STATES PATENT OFFICE.

RAYMOND C. MERCER, OF LOS ANGELES, CALIFORNIA.

FILM-PATCH.

1,389,523.

Specification of Letters Patent. Patented Aug. 30, 1921.

Application filed June 1, 1920. Serial No. 385,784.

To all whom it may concern:

Be it known that I, RAYMOND C. MERCER, a citizen of the United States, residing at Los Angeles, in the county of Los Angeles and State of California, have invented a new and useful Film-Patch, of which the following is a specification.

My invention relates to the art of motion picture film, being more particularly a device for fastening together ends of film. In the production of motion pictures it frequently happens during the various operations of printing, developing, drying the film and making up the film that the film is broken, and it is the principal object of my invention to produce a film patch of simple form and construction, which may be readily used for securing the ends of film together, such patch being of such a nature that the same may be used over a great number of times.

The invention consists in general terms of a patch preferably formed of sheet metal consisting of a sheet metal body portion having fingers or prongs formed thereon.

Further objects and advantages will appear hereinafter from the following specification.

Referring to the drawings, which are for illustrative purposes only,—

Figure 1 is a perspective view of a portion of two pieces of film having their ends joined together and secured by means of a patch embodying a form of my invention.

Fig. 2 is a perspective view of the patch shown in Fig. 1.

Fig. 3 is an end view of the patch, the film being shown in section, such view illustrating the position of the patch in position about to be used on the film.

Fig. 4 is a view similar to Fig. 3, showing a patch as the same appears when the operation of patching the film is partly completed.

Fig. 5 is a view similar to Figs. 3 and 4 showing the patch in place.

Fig. 6 is an end view of a modified form of patch.

Fig. 7 is a cross-sectional view of two pieces of film showing the form of patch disclosed in Fig. 6 fastened thereto.

Fig. 8 is a plan view of another modified form of patch; and

Fig. 9 is an enlarged side view of the patch shown in Fig. 8.

The patch shown in Figs. 1 to 5, inclusive,

consists of a plate 11 each side of which is provided with a series of outwardly extending fingers or spurs 12, such fingers being rounded on their ends as indicated at 13 and 60 being of a proper size to enter the perforations 14 on the sides of the film indicated at 15, such film being what is commonly known as moving picture film. The patch is preferably made of German silver or a 65 metal which is not subject to the action of the chemicals used in the development of the film, but it is to be understood that the patch may be made of other materials without departing from the spirit of my invention. 70

The patch is preferably bowed or bent as shown in Figs. 2 and 3, the angle of the fingers 12 of the patch being such that they are in proper position to enter the perforations in the film when placed in the position shown in Fig. 3. It is to be understood that the patch is frequently used in the dark room and that by making the patch in the form shown in Figs. 2 and 3 that it is 80 a very simple matter to bring the two ends of film to be patched together upon each other and insert the fingers on the patch through the corresponding perforations in the ends of the film. 85

This procedure of patching the film is carried out as indicated in Figs. 3 to 5, inclusive, Fig. 3 showing the patch about to be applied to the overlapping ends of film; Fig. 4 the fingers partially inserted through the perforations in the film after which operation the patch is bent flat as indicated in Fig. 5, in which position the fingers are entirely inserted through the perforations in the film and the film appears as shown in 95 Fig. 1.

It is also to be noted that the patch is of approximately the width of what is known as a frame, such as indicated at 17 in Fig. 1, that is, the space taken up on the film by 100 a single scene. By making the patch approximately of the width indicated but very little of the film is taken up by the patching operation, this being quite important when the break occurs in the film, and it is necessary to patch the same during that portion of the film which is known as "action", that is, a scene in which the figures are in rapid motion, and to destroy a number of frames would interfere with the proper 110 reproduction of the action. Ordinarily patches of this kind are made by doubling

over several thicknesses of the two ends of film and pinning the same together, this being done in many instances in the dark room as above referred to, the operators 5 continually injure their hands from such operations. Such objectionable feature is avoided by the patch herein shown and described.

A further advantage of the patch is that 10 the ends of the film and the patch are flat and are comparatively in a straight line so that no bump or free ends project from the film, and further, the plurality of teeth engaging the film on each side of the patch 15 produce a strong patch which is particularly desirable when film is placed on the drums for drying, as under such circumstances the film tightens up on the rack and unless the patch is strong the film breaks 20 at the patch.

In the form shown in Figs. 6 and 7, the patch indicated at 20 consists of a flat sheet 21 having downwardly extending fingers or spurs 22. In using this patch the fingers 25 or spurs are inserted in the perforations indicated at 23 in the film 24 and bent back upon the film as indicated at 25. In the form of patch shown in Figs. 8 and 9 the fingers 27 are preferably rounded as indicated at 28 for the purpose of reducing the 30 liability of tearing the film.

In all the forms shown the film after being patched may be readily handled without fear of injury to the film or to the operators as the patch has no portion thereof 35 which projects from the film, the fingers in the forms shown in Figs. 1 to 5, inclusive, and Figs. 8 and 9 being of approximately the same width as the film. In the

form shown in Figs. 6 and 7 the fingers 40 may be longer than in the other form as in this form they are bent back upon the film.

What I claim is:—

1. A film patch for connecting the overlapped ends of perforated motion picture film comprising a member having a flat body and projections of substantially uniform width formed on said body arranged to extend substantially in the same plane as the body portion through corresponding perforations along the edges of the overlapped ends of the film. 45

2. A film patch for connecting the overlapped ends of perforated film comprising a body member formed of thin sheet metal 55 having teeth formed on each side thereof extending outwardly from each side of the body portion, said teeth being spaced apart corresponding to the spacing of the perforations along the edges of the standard motion picture film and when inserted in the film extending substantially in the same plane as the body portion. 60

3. A film patch for connecting the overlapped ends of perforated film comprising a body member formed of thin sheet metal curved in cross-section, said member having a plurality of projections of substantially uniform width extending outwardly from each side thereof substantially 65 in the same plane as the body portion and properly spaced apart to engage the perforations in the edges of the film. 70

In testimony whereof, I have hereunto set my hand at Los Angeles, California, this 75 21st day of May, 1920.

RAYMOND C. MERCER.
